SIZING DEVICE FOR WINDING MACHINES

William Shontz, Lewistown, Pa., assignor to
American Viscose Corporation, Wilmington,
Del., a corporation of Delaware

Application June 3, 1943, Serial No. 489,432

8 Claims. (Cl. 242—37)

This invention relates to winding machines and more particularly to an improved device for arresting the operation of the machine when the package being wound reaches a predetermined size.

The present invention is particularly directed to winding machines of the type generally disclosed in United States Patent No. 801,941 to Wardwell, wherein the yarn is wound upon a supporting element, such as a core, mounted on a rotating spindle, the yarn being traversed longitudinally of the core by a thread guide that bears against the surface of the winding and swings away from the spindle as the wound package increases in size. The form of device for stopping the winding machine generally employed with this type of winding machine and shown in the Wardwell patent has the disadvantages of being somewhat slow-acting and of increasing the pressure of the thread guide against the surface of the winding as the package approaches the predetermined size to which the stopping device has been set. The slow-acting characteristic of the device results in cakes of non-uniform weight but, what is more important, the increased pressure in the package during actuation of the stopping device deforms the cake. The stopping device shown in United States Patent No. 2,116,453 is similarly slow-acting.

It is an object of the invention to provide a novel form of device for automatically stopping the winding when the package reaches a predetermined size which device acts suddenly and avoids the exertion of undue pressure of the guide against the package. Another object is to provide such a device which is simple in character and which may be readily attached to standard machines without altering the structure thereof. Another object is to provide such a device which is adapted to cooperate with the mechanism for stopping the device automatically upon breakage or exhaustion of the supply of the yarn or strand being wound. A further object is to provide a device which is adjustable in character so that a package of any desired size may be obtained upon the machine or machines to which the attachment is applied. Other objects and advantages will appear from the drawing and description thereof.

In the drawing, illustrative of the invention,

Figure 1 is a front elevational view of a conventional type of winding machine showing the present invention applied thereto,

Figure 2 is a side elevational view of the winding machine shown in Figure 1.

Figure 3 is a front elevational view showing a modification.

5 Figure 4 is a front elevational view showing another modification, and

Figure 5 is a side elevational view of the modification of Figure 4.

While the invention will be described herein-
10 after in relation to a particular type of conventional winding machine, it is to be understood that it is not limited to application thereto. In the description, the conventional parts of the winding machine will first be described and this
15 will be followed by a description of the parts which constitute the present invention.

Referring to Figures 1 and 2 of the drawing, reference numeral 2 designates the fixed main frame of the machine. At the top of frame 2,
20 a rotating spindle 3 is journaled in suitable bearings and is adapted to be driven by means of a belt and pulley or other suitable mechanism (not shown). The spindle is adapted to receive a cone or cop tube 4 upon which the package 5 is to be
25 wound.

A shaft 6 is journaled in the frame 2 and extends in a direction parallel to the winding spindle 3. This shaft 6 is connected to the spindle and is driven therefrom by suitable means, such
30 as gears, a belt and pulleys, sprockets and chain (not shown). The shaft 6 also carries a helical grooved cam 7 for rotation therewith.

A traverse frame 8 is pivotally mounted upon the shaft 6 upon which it is suitably balanced
35 such as by the counterweight 9. This traverse frame 8 is provided with a backing plate 10 and a porcelain bail 11 may be rotatably supported on a wire 12 whose depending legs adjacent the ends of the bail are suitably fastened within recesses in the plate 10. The traverse frame 8 is constructed to provide a horizontal groove through which a traverse bar 13 may reciprocate. A thread guide 14, whose upper end is adapted
40 to press lightly against the package being wound is fastened to one end of the traverse bar 13 for reciprocation therewith. The other end of the traverse bar 13 is provided with a sliding head 15 having a depending pin or roller 16 adapted to engage the groove in the helical cam 7. There
45 is a shoulder 17 upon the sliding head 15 at its point of juncture with the traverse bar 13. As the package builds up, it gradually swings the traverse frame 8 away from the spindle 3 and the traverse frame is prevented from swinging back toward the spindle by means of a lever 18
50

having one end fastened thereto at 19 and the other end engaging within a groove formed underneath a segment 20 which is pivotally fastened to the main frame 2 at 21.

The operation of the winding machine is controlled by a starting lever or handle 22, mounted on one end of a rotatable rod 23, supported in bearings at the top of the main frame 2. The opposite end of the rod 23 carries means for operating a clutch or similar device (not shown) to control the operation of the spindle 3 and the other parts of the machine driven therefrom. A lever 24 is mounted adjacent the starting lever 22 on the rod 23 so that it rocks therewith. One end of lever 24 is normally biased in a counter-clockwise direction by a spring 25 fastened to the frame 2 and is provided with a braking means 26 which is adapted to press against the spindle 3 and to stop the rotation thereof when the lever 22 is in the stop position in which position the clutch or other device for operating the spindle 3 is disengaged. The other end of the lever 24 is formed as curved arm having a hook 27 at its end. When the starting lever 22 is in operating position, in which the clutch is engaged with the spindle 3 and the brake is lifted therefrom (as shown in Figure 1), the hook 27 engages another hook 28 secured to or constituting part of the pivoted segment 20. The machine may be maintained in running position by setting these hooks 27 and 28 in opposition to the spring 25 which otherwise would tend to set the brake and to swing the starting lever 22 into the stop position.

In operation of the machine shown in Figures 1 and 2, the yarn passes first through a tension device 29 over the guide 30, under a break or exhaustion detector 31, over the porcelain bail 11 and through the traverse guide 14 to the package. The break detector 31 comprises a device pivotally mounted at 32 upon segment 20. The device is composed of two arms 33 and 34, one of which 33 extends toward a wheel 35 having numerous projections or ridges 36 thereon mounted upon the cam shaft 8 for rotation thereby. The other arm 34 is bent to form a horizontal extension 37 adapted to ride upon the yarn and along which the yarn may traverse to a certain extent. The extension 37 may be bent at the end to form a hook 38 to prevent the yarn from accidentally slipping out of engagement therewith. The first arm 33 is of such length and the entire detector device 31 is so balanced that upon breakage of the yarn, the device swings in a clockwise direction to bring arm 33 into the path of the projections 36 upon the rotating wheel 35 which in turn forces the segment 20 in a counterclockwise direction sufficiently to release the two hooks 27 and 28 and thereby permit the spring 25 to throw the starting lever 22 into the stop position to apply the brake and disengage the clutch. A projection 39 is provided to limit the clockwise motion of the arm 34.

The parts of the machine so far described are conventional and constitute no essential part of this invention except as will appear hereinafter.

In accordance with this invention, the segment 20 is provided with an additional sizing knock-off arm 40 pivotally mounted thereon. The pivoted axis portion of this arm extends through a bore in a block 41 which it carries back of the segment 20. Another rod 42 (which may be straight as shown or of an arcuate shape corresponding to the arc of the segment 20) extends through a bore in the block extending approximately at right angles to the first bore and having its center

line somewhat beneath that of the first bore so that they intercommunicate. By flattening the top surface of the rod 42, it is readily adjustable axially through its cooperating bore in the block 5 and may be fixed at any desired position by tightening the set screw 43, which action also fixes the axis portion of arm 40 in the block. As shown in Figure 1 the rod 42 has an upwardly extending portion which has a portion 44 overhanging the segment 20 thereby limiting the counterclockwise motion of this sizing knock-off system so that the end of arm 40 normally rests in proximity to the ridged wheel 35.

In operation of the sizing device of Figures 1 and 2, the rod 42 is set in a predetermined position according to the size of package desired by means of the set screw 43. As the package builds up, the traverse frame 8 is swung clockwise as viewed in Figure 1 until a position is reached 15 where the shoulder 17 of the traverse bar sliding head strikes it. Such striking is sudden and effects immediate swinging of the arm 40 into the ridged wheel 35 and stoppage of the machine.

Figure 3 shows a modification in which the arm 25 33 of the end breakage detector is pivotally supported at 45 with respect to the pivotal mounting 46 for the breakage detector arm 34'. Arm 33 normally rests against the stop 47 in the position shown. The sizing knock-off is the same as that 30 of Figures 1 and 2, except that the rod 40' is arranged to kick the arm 33' into the ridged wheel 35' instead of swinging its own end directly into the wheel 35'. For this purpose rod 40' may be provided with a projection 48 against which 35 arm 33' normally rests as shown.

Figures 4 and 5 show another modification in which the sizing stop or knock-off device is connected with the end breakage detector. As shown, the arm 33a of the end breakage detector of type 40 similar to that shown in Figure 3 has its pivotal axis or shaft 49 extending through segment 20a to the back thereof where it carries block 41a which in turn carries the arm 42a terminating in the hook 44a. The arm 34a is secured in a block 50 which is free to pivot on the shaft 49. The block 50 is provided with a pin 41a for effecting swinging of the arm 33a when breakage of an end occurs. The whole system as a unit is balanced 45 so that it tends to swing the arm 33a into the ridged wheel 35a upon breakage or release or tension of the yarn passing under the horizontal portion 37a of arm 34a.

While the sizing stop device has been shown 55 where it is arranged to be actuated by a shoulder 17 (17' or 17a) at the juncture of the traverse rod 13 (13' or 13a) and the sliding head 15 (15' and 15a), it is to be understood that it may be arranged for cooperation with any suitable projection, shoulder, or tapered section of the traverse 60 rod or its sliding head or the end of the traverse rod itself. To facilitate this, rod 42 (42' or 42a) may be arranged either alongside or in front of the segment instead of to the rear thereof as shown.

65 From the description of the device of the invention, it is apparent that it is quick in action and involves only a practically instantaneous application of a slight amount of pressure. It is simple in character, readily attachable to any winding machine and is easily adjusted.

In the present specification and claims, the term "package" is used in a general sense to indicate any form of wound mass and the term "yarn" is intended to designate any kind of strand 70 material whether textile or otherwise.

While a preferred embodiment of the invention has been disclosed, it is to be understood that changes and variations may be made without departing from the spirit and scope of the invention as defined by the appended claims.

I claim:

1. In a winding machine, a winding spindle, a traverse mechanism comprising a reciprocating member, means for swinging the spindle and traverse mechanism relative to each other as the winding proceeds, means for stopping the machine automatically comprising an element constantly driven during operation of the machine and a stop member movable into engagement with the driven element to initiate the operation of the stop means, the stop member having an extension thereof positioned in the path of the reciprocating member so that the stop member is moved thereby to initiate the stop means upon the winding of a predetermined size of package.

2. In a winding machine, a winding spindle, a traverse mechanism comprising a reciprocating member, means for swinging the spindle and traverse mechanism relative to each other as the winding proceeds, means for stopping the machine automatically comprising an element constantly driven during operation of the machine and a stop member having an arm movable into engagement with the driven element to initiate the operation of the stop means, the stop member having a second arm positioned in the path of the reciprocating member so that the stop member is moved thereby to initiate the stop means upon the winding of a predetermined size of package.

3. In a winding machine, a winding spindle, a traverse mechanism comprising a reciprocating member, means for swinging the spindle and traverse mechanism relative to each other as the winding proceeds, means for stopping the machine automatically comprising an element constantly driven during operation of the machine and a stop member movable into engagement with the driven element to initiate the operation of the stop means, an actuating member cooperating with the stop member and having a portion extending into the path of the reciprocating member so that the stop member is moved thereby through the actuating member to initiate the stop means upon the winding of a predetermined size of package.

4. In a winding machine, a winding spindle, a traverse mechanism comprising a reciprocating member having a projection, means for swinging the spindle and traverse mechanism relative to each other as the winding proceeds, means for stopping the machine automatically comprising an element constantly driven during operation of the machine and a stop member movable into engagement with the driven element to initiate the operation of the stop means, an actuating member cooperating with the stop member and having a portion extending into the path of the projection on the reciprocating member so that the stop member is moved thereby through the actuating member to initiate the stop means upon the winding of a predetermined size of package.

5. In a winding machine, a winding spindle, a traverse mechanism comprising a reciprocating member, means for swinging the spindle and traverse mechanism relative to each other as the

winding proceeds, means for stopping the machine automatically comprising an element constantly driven during operation of the machine and a stop member movable into engagement with the driven element to initiate the operation of the stop means, a detector element responsive to breakage and exhaustion of the yarn being wound connected to and arranged to move the stop member to initiate the stop means and a second detector element responsive to a predetermined size of winding arranged to move the stop member and positioned in the path of the reciprocating member to be actuated thereby.

6. In a winding machine, a winding spindle, a traverse mechanism comprising a reciprocating member having a projection, means for swinging the spindle and traverse mechanism relative to each other as the winding proceeds, means for stopping the machine automatically comprising an element constantly driven during operation of the machine and a stop member movable into engagement with the driven element to initiate the operation of the stop means, a detector element responsive to breakage and exhaustion of the yarn being wound connected to and arranged to move the stop member to initiate the stop means and a second detector element responsive to a predetermined size of winding arranged to move the stop member and positioned in the path of the projection of the reciprocating member to be actuated thereby.

7. In a winding machine, a winding spindle, a traverse member having a projection, means for swinging the spindle and traverse mechanism relative to each other as the winding proceeds, means for stopping the machine automatically comprising an element constantly rotated during operation of the machine and a pivotally mounted stop member movable into engagement with the rotated element to initiate the operation of the stop means, an arm connected to the stop member and arranged to move the stop member to initiate the stop means in response to breakage and exhaustion of the yarn being wound, a detector device having an arm arranged in the path of the projection on the reciprocating member and having a second arm arranged to move the stop member to initiate the stop means upon the striking of the first arm by the projection.

8. In a winding machine, a winding spindle, a traverse mechanism comprising a reciprocating member having a projection, means for swinging the spindle and traverse mechanism relative to each other as the winding proceeds, means for stopping the machine automatically comprising an element constantly rotated during operation of the machine and a pivotally mounted stop member movable into engagement with the rotated element to initiate the operation of the stop means, an arm connected to the stop member and arranged to move the stop member to initiate the stop means in response to breakage and exhaustion of the yarn being wound, a second arm connected to the stop member for motion with the stop member and being positioned in the path of the projection on the reciprocating member so that initiation of the stop means is effected upon the striking of the second arm by the projection.
